SLICER

Florian B. Pedersen, San Leandro, Calif.

Application November 8, 1943, Serial No. 509,355

3 Claims. (Cl. 30—116)

1.

My invention relates to an improved device for slicing material, such as cheese or butter; and the broad object of the invention is to provide a simple, hand operated slicing instrument having a guide roller for controlling the thickness of slice.

More specific objects of my invention include the provision of an improved frame structure for supporting the guide roller and cutting element, and improved means for holding the roller in a selected position of adjustment.

The invention possesses other objects and features of advantage, some of which, with the foregoing, will be set forth in the following description of my invention. It is to be understood that I do not limit myself to this disclosure of species of my invention, as I may adopt variant embodiments thereof within the scope of the claims.

Referring to the drawings:

Figure 1 is a side elevational view of a slicer embodying the improvements of my invention;

Figure 2 is a fragmentary view on larger scale, partly in section and partly in elevation, showing the roller mounting;

Figure 3 is a detail view, also on larger scale, showing how the cutter wire is fastened to a tie arm;

Figure 4 is a perspective view showing a modified frame structure;

Figure 5 is a side elevational view showing another modification;

Figure 6 shows a slicer with a different type of handle;

Figure 7 illustrates a modified structure having a guide arm for the roller; and

Figure 8 is a detail view of the sleeve and guide arm for the roller shown in Figure 7.

In terms of broad inclusion, my slicer comprises a frame providing a journal for a guide roller and support for a cutting element. The guide roller is preferably conical in shape, and is slidably arranged on the frame so that the line of rolling contact is maintained parallel with the cutting element, whereby sliding the roller along its axis adjusts the thickness of slice. My present invention is directed primarily to improvements in the frame structure and mounting for the roller.

In greater detail, and referring particularly to Figures 1 to 3 of the drawings, the slicer embodying my invention comprises a frame shaped from heavy wire or rod material, and having a straight portion providing an axle 2 terminating at one end in a loop providing a handle 3. The end of the rod at the handle extends transversely across

2.

axle portion 2 to provide a tie arm 4 lying substantially in the plane of the handle loop. Another tie arm 6 is formed at the opposite end of axle 2; preferably by bending the end of the rod outwardly to lie in the direction of and substantially parallel with arm 4. The frame, including the axle, handle, and tie arms, is thus formed integrally from a single piece of rod material. Bending may be done in a suitable die, and the final bend at arm 6 is preferably effected after certain other parts of the device have been assembled.

A guide roller 7 is slidably journaled on axle 2, and a taut cutting element or wire 8 is connected between tie arms 4 and 6. The guide roller is preferably conical in shape, and cutting element 8 is inclined to the axis of the roller so that the line of rolling contact is maintained parallel with the cutting element. Shifting the guide roller along axle 2 controls the thickness of slice; and this is facilitated by graduations 10 stamped on the axle. Shifting the roller to the left in Figure 1 operates to increase the thickness of slice, while shifting the roller to the right serves to decrease the thickness of slice.

Since the line of rolling contact is parallel to the cutting element there is little tendency for the roller to shift laterally, but I prefer to provide means to hold the roller in a selected position. As shown in Figure 2, a core sleeve 9 upon which the roller is journaled is slidably mounted on axle 2. The sleeve may be a complete tube, or drawn from a flat sheet with a longitudinal slot left between adjacent edges. Each end of the sleeve has an axially extending slot 11 and an annular groove 12 lying across the slot. Slots 11 extend through both walls of the sleeve; and groove 12 is preferably formed by rolling. Split collar 13 is seated in groove 12 at each end of roller 7, and functions as a retainer for the roller and also as means for compressing the sleeve into frictional engagement with the axle. The slot and groove arrangement allows collar 13 to be readily slipped into seated position for convenience in assembly, and also provides for the desired frictional engagement between the sleeve and axle due to the compression of the sleeve when the collar is finally seated. The frictional engagement is preferably relatively light to allow free axial adjustment of the roller, since little force is required to keep the roller in adjusted position during operation of the unit.

As shown in Figure 3, cutting wire 8 is preferably fastened by wrapping say twice around the tie arm and then clamping the end of the

wire in a slot 14 cut in the end of the arm. This method of tying the wire is simple and I have found it very effective. When the cutting wire is applied it is put under sufficient tension to insure that the wire will be taut. In my improved frame structure there is additional assurance that the cutting element will be taut during operation of the slicer, because when an operator grasps the handle 3 the tie arms 4 and 6 tend to spread and thus further tension the cutting element.

Figure 4 shows a modified frame structure in which tie arm 4 is bent to lie at substantially right angles to the plane of handle loop 3. The other tie arm 16 is formed from a separate piece with an aperture press fitted on a squared end 17 of the axle. Pointed ears 18 are also preferably provided on the end piece, extending oppositely from arm 16. These pointed ears provide a fork for picking up or moving the sliced material.

In the modification shown in Figure 5, a portion of the frame rod extends back along the axle to form a bridge 19 terminating in a tie arm 21 extending transversely across the end of axle 2. This tie arm is also recessed to provide a socket for pointed end 22 of the axle, thus giving support for the latter. The portions of the rod between handle 3 and bridge 19 are preferably shaped into a loop 23 extending transversely of the axle to provide the other tie arm for cutting element 8. Loop 23 preferably straddles axle portion 2 for further rigidity; and it will be observed that tension in cutting element 8 tends to hold pointed end 22 of the axle in seated position.

In the modification shown in Figure 6 a separate handle 24, such as wood, is provided, and axle 2 terminates at one end in a pointed tang 26 seated in the handle. Tie arm 27 is preferably formed as a separate piece having an aperture engaging the axle, and also preferably having an outturned tang 27a penetrating the end of the handle. The axle 2 has its outer end turned to form the arm 28. One end of cutting wire 8 is secured around the end of arm 28 as described in connection with Figures 1 and 3; and the other end is clamped under fingers 29 stamped out of the tie arm 27.

Figure 7 shows still another modification of my invention, comprising a frame having a handle portion 30 connected by spreader bars 31 to tie arms 32. In this case axle 33 is formed as a separate piece seated in suitable sockets formed in arms 32 and held by the taut cutting element 8. Guide roller 7 is preferably journaled on a

sleeve 34 clamped by a nut 36 threaded on a split end of the sleeve. An arm 37 is preferably secured to the other end of the sleeve and terminates in a forked portion 38 slidably engaging one of the spreader bars 31 of the frame. Graduations on the spreader bar facilitate setting the roller to a selected thickness of slice.

I claim:

1. A slicer comprising a handle, an axle terminating in a pointed end penetrating the handle, a laterally extending tie arm engaging the axle adjacent the handle and secured to the inner end of said handle, a second laterally extending tie arm at the other end of the axle, a guide roller journaled on the axle, and a cutting element connected to and extending between said arms.
2. A slicer comprising an axle, a pair of arms carried by the axle and extending laterally therefrom in spaced relation, a cutting wire secured to and stretched taut between the arms, a sleeve slidable on the axle between the arms and having slotted ends, collars for compressing the slotted ends of the sleeve into frictional engagement with the axle, and a guide roller journaled on the sleeve.
3. A slicer comprising an axle, a pair of arms carried by the axle and extending laterally therefrom in spaced relation, a cutting wire secured to and stretched taut between the arms, a sleeve slidable on the axle between the arms and having a slotted end with an annular groove transversely of the slot, a collar seated in the groove, and a guide roller journaled on the sleeve.

FLORIAN B. PEDERSEN.
